[57] CLAIM

The ornamental design for an air-operated cleaner, as shown and described.

DESCRIPTION

FIG. 1 is a perspective view of an air-operated cleaner showing my new design;

FIG. 2 is a side elevational view the opposite side being a mirror image thereof;

FIG. 3 is a front elevational view thereof;

FIG. 4 is a top plan view thereof, and

FIG. 5 is a bottom plan view thereof.

The hose has been shown fragmentary in FIGS. 1, 2 and 4 for convenience of illustration.
